NATHANIEL E. LOOMIS, OF ELIZABETH, NEW JERSEY, AND WARREN K. LEWIS, OF CAMBRIDGE, MASSACHUSETTS, ASSIGNEES TO STANDARD OIL DEVELOPMENT COMPANY, A CORPORATION OF DELAWARE

VACUUM DISTILLATION AND RECTIFICATION OF PARAFFIN DISTILLATE

Application filed June 2, 1924. Serial No. 717,226.

This invention relates to the preparation of hydrocarbon products, and will be understood from the following description, taken in connection with the accompanying drawing, which represents diagrammatically apparatus which may be used for practice of the invention.

In the customary procedure of obtaining high viscosity distillate lubricating oils and crystalline wax from paraffin base petroleum, the oil is distilled to coke bottoms in coking stills at atmospheric pressure, naphtha being taken off as the first distillate, and the distillates becoming progressively heavier as the temperature increases. When the heavier or more viscous lubricating constituents are distilling over, the temperature of the still is within the cracking range, and it has been generally believed heretofore that a certain amount of cracking was necessary in order to secure a high boiling point paraffin distillate in which the wax content would be of such character as to permit of separation of the wax by chilling and filter-pressing.

By the procedure referred to, i. e., by resorting to a mild but well defined and important "cracking", it has been possible to obtain all but the very heaviest portion of the paraffin distillate as a single fraction which could be chilled and filter-pressed in the ordinary way to yield a low-cold-test lubricating distillate ready for further refining, and a slack wax of dominantly crystalline character from which, by the recognized methods of sweating and treating and decolorizing, a crude scale or refined scale wax of merchantable quality can be made. The remainder of the paraffin carrying distillate, which might amount to the heaviest 20% thereof, is of such character that it cannot be directly handled as above described. It is common to rerun this product, known as "paraffin slop", in coking stills, thus subjecting it to a second cracking, and by this means to secure the major portion of it as a distillate similar in quality to the original paraffin distillate. The unfit portion of the distillate resulting from this rerunning operation, i. e., the paraffin slop from paraffin slop, is remixed with

straight paraffin slop and in this way eventually disposed of.

Where it is desired to produce primarily a viscous residual lubricating oil rather than a viscous distillate oil from paraffin base crude, the original distillation must obviously be accomplished without substantial cracking. In this case, the first portion of the paraffin distillate, i. e., the lowest boiling fraction thereof, amounting to perhaps 50% of the total, is cut directly as a single fraction on the crude distillation, but in the absence of the cracking referred to, the second portion, in amount up to about one-half the total is of "unfit" character. This unfit paraffin distillate or paraffin slop from crude distillation operations in which cracking is reduced to a minimum, is therefore large in amount. It is commonly handled by rerunning under conditions involving well defined cracking and thus separated into a fit and an unfit portion as above described.

In the present state of the art there is no method known to refiners for producing from a paraffin bearing crude oil, such as Pennsylvania or Mid-continent crude, a quality of heavy or viscous paraffin distillate which will give a viscous low-cold-test lubricating distillate and a dominantly crystalline dry wax cake by the universally used chilling and filter-pressing methods, without subjecting the heavier wax-bearing constituents of the oil to a well defined cracking operation, either as a part of the original distillation of the crude oil or in a subsequent rerunning of the crude distillate.

In the accompanying drawings, Fig. 1 is a diagrammatic horizontal plan of apparatus in which our method may be practiced; and

Fig. 2 is a sectional detail, showing a portion of a rectifying column.

In proceeding in accordance with the present invention, oil which contains paraffin is distilled, taking off cuts of lighter distillate as desired, and while substantially avoiding cracking, as for example by application of a vacuum, the lubricating constituents are taken off, dissolved wax coming also therewith. By adequate rectification a heavy or viscous paraffin distillate is obtained which

is readily pressable on filter presses to separate out the wax in the ordinary way, and the destruction of a part of the wax and a part of the lubricating oil by cracking as in the practice above referred to is avoided. We have found then that the yields of products realized by the use of our process are materially greater than the yields obtained by operating under present practice. According to our new process the distillation may be carried out in batch stills if desired, raising the temperature for the successive cuts of distillate, and applying adequate fractionation and a vacuum while the paraffin distillate is coming over, or preferably a continuous battery of stills may be used, for example referring to the drawing a series of stills are arranged in a battery. As illustrated, three stills 1, 2, 3 are shown, but it will be understood that these are part of a continuous battery comprising as many stills as desired and having a flow line 4 and fractionating towers 5, 6, and 7. The fractionating towers may be of any suitable construction provided that they are capable of effecting an accurate fractionation. We prefer to employ plate columns, the plates being perforated to allow vapors to bubble through layers of accumulated liquid, and with or without bell-caps. Each tower has a final condenser, such as water-cooled condenser 8 and a receiver. From the receivers of the stills which are to be under vacuum, for example receivers 9 and 10, connections 11 lead to a vacuum-producing means, as pump 12.

With the stills all heated to the respective temperatures for taking off their successive cuts, and a vacuum being applied to the stills taking off the last cuts of distillate (for illustration a vacuum corresponding to an absolute pressure substantially equivalent to 30 mm. of mercury to allow a final-still temperature of not over 640° F.), from the earlier stills in the series there will successively come off naphtha, water white oil, etc., and from the vacuum still 2 a viscous paraffin distillate or lubricating fraction containing dissolved wax. As the paraffin distillate vapors pass through successive rectification zones in the tower, the constituents are progressively fractionated and the condensate obtained in the receiver 10 is available to be forwarded by a pump 13 through a chiller 14 to cause dissolved paraffin wax to form crystals, and then by a pump 15 to the filter-press 16 where the wax is removed as a dry dominantly crystalline cake. The paraffin wax is dissolved in the petroleum lubricating oil with which it was simultaneously evolved from the successive rectification zones. It is cooled in the chiller 14 (in accordance with established practice) to a temperature at which substantial quantities of crystalline paraffin wax are formed. It may, for example, be

cooled to a temperature of 30° to 15° F. before pressing. The yield of paraffin distillate viz, paraffin-bearing lubricating oil of good quality obtained directly and without cracking in this way will be equal to or greater than the total yield of distillate representing that cut directly from the crude oil and that obtained from rerunning the unfit distillate, according to the prior processes. It will be in all respects of as good quality, containing the same percentage of viscous lubricating fractions and of wax. From the last still 3 a further quantity of paraffin distillate is secured which is of very high viscosity and contains a further quantity of paraffin wax, a separation of which can be effected by similar treatment.

By our process, therefore, we obtain directly from the wax-bearing oil, such as paraffin-base crude oil, a full yield of paraffin distillate of a quality equal to that heretofore obtained only by resorting to cracking; but we obtain in addition an important additional yield of viscous paraffin distillate, which we believe to represent the constituents heretofore destroyed or sacrificed in order to obtain the quality and yield of the paraffin distillate previously obtainable. The additional paraffin distillate obtained by our process therefore represents a net gain of viscous lubricating oils and paraffin wax. The procedure used for further refining of this additional distillate may be either that heretofore known and used for oils of generally similar properties, or it may be the same here described, or it may be a combination of these.

Although the full advantage of the above invention can be realized only when cracking is reduced to a minimum, as by the use of a high vacuum, it will be understood that a considerable part of the benefit can be realized by adequate fractionation during a continuous distillation in which the reduction of the still temperatures and consequent reduction of cracking is accomplished by the use of relatively large quantities of steam.

We claim:

1. The method of obtaining high yields of a pressable paraffin distillate from a paraffin-bearing crude petroleum from which constituents of lower boiling point than lubricating oil have been substantially removed which comprises heating the crude oil to a temperature sufficient to cause vaporization and rectifying the vapor under vacuum to produce an overhead vapor consisting of paraffin distillate.

2. The method of obtaining high yields of a pressable paraffin distillate from a paraffin-bearing crude petroleum from which constituents of lower boiling point than lubricating oil have been substantially removed, which comprises heating the crude oil to a temperature sufficient to cause vaporization,

rectifying the vapor under vacuum to produce an overhead vapor consisting of paraffin distillate, conducting away and condensing the vapor.

5 3. The method of obtaining high yields of a pressable paraffin distillate from a paraffin-bearing crude petroleum from which constituents of lower boiling point than lubricating oil have been substantially removed, 10 which comprises heating the crude oil to a temperature sufficient to cause vaporization, conducting the vapor to a group of fractionation zones in communication, each of which zones comprises liquid and vapor phases in 15 partial equilibrium and under vacuum to produce a rectified vapor consisting of paraffin distillate.

20 4. Method according to claim 3 in which the vapor produced is conducted away, condensed, cooled to the point at which paraffin precipitates in crystalline form and filtered to produce a residue of paraffin wax and a filtrate of petroleum lubricating oil.

25 5. Method according to claim 3 in which the crude oil is heated to a temperature not exceeding 640° F.

30 6. Method according to claim 3 in which the crude oil is maintained during the heating under an absolute pressure of not exceeding 30 mm. of mercury.

35 7. Method according to claim 3 in which the crude oil is heated to a temperature not exceeding 640° F. under an absolute pressure not exceeding 30 mm. of mercury.
